(57) **CLAIM**

The ornamental design for a light cover with faux alabaster appearance, as shown and described.

DESCRIPTION

FIG. 1 is a side view of a light cover with faux alabaster appearance;

FIG. 2 is a top view thereof; and,

FIG. 3 is a bottom view thereof.

The glass of the cover is translucent, with irregular swirls formed by lines which are more opaque than intervening regions, creating an appearance similar to alabaster.
